ACETYLENE GENERATOR VALVE MECHANISM

Filed May 1, 1943

UNITED STATES PATENT OFFICE

2,387,347

ACETYLENE GENERATOR VALVE
MECHANISMRalph C. Pierson, Indianapolis, Ind., assignor to
Union Carbide and Carbon Corporation, a cor-
poration of New York

Application May 1, 1943, Serial No. 485,302

3 Claims. (Cl. 251—44)

This invention relates to acetylene generators of the carbide-to-water type, and more particularly to the carbide feed valve mechanism thereof.

The novel features of the invention are particularly adaptable for use with medium pressure acetylene generators of the type disclosed in Patent No. 2,188,278 of Maurice P. DeMotte, dated January 23, 1940. In generators of such type a carbide feed lever is provided for supporting a carbide feed valve and operating such valve with respect to the carbide outlet opening of a carbide hopper, the arrangement being such that when the carbide feed lever is actuated in the one direction, carbide is fed through such opening to water to generate acetylene, and when such lever is actuated in the opposite direction, such opening is closed. In such construction the carbide feed lever is pivotally connected to a bracket which is in turn fixed with respect to the carbide hopper. The feed lever is actuated by a pressure controlled, spring opposed diaphragm and also by a manually operated feed lock cam. In manufacturing the generator the parts must be made to accurate dimensions and carefully assembled so that the carbide feed valve, which is mounted on the lever, will be in proper position with respect to the carbide feed opening, because any misalignment of the valve with the opening results in the leakage of water vapor from the generating chamber to the carbide hopper when the generator is not in use, which is very undesirable. In addition, the carbide feed lever must be in proper position with respect to the feed lock cam in both the open and closed positions. Such generators are also subject to the difficulty of positioning the valve in proper vertical position with respect to the opening in the carbide hopper so that the valve will properly close when actuated by the carbide feed lever.

The main objects of the present invention, therefore, are to provide an improved valve mechanism for feeding granular material by gravity, the elements of which mechanism may be more quickly assembled and more nicely adjusted than those known to the prior art; an adjustable feed lever and valve arrangement that is not only a time saver in assembling but which is capable of precise and easy adjustment in the field, of the carbide feed valve in relation to the hopper opening and other elements of the feed mechanism; an adjustable connection between the feed lever and valve for centering the latter with respect to the carbide hopper opening and for changing the axial position of the valve with respect to such opening; and means for adjusting the position of

the carbide feed lever with respect to the feed lock cam.

In accordance with the invention there is provided in a carbide-to-water acetylene generator, the combination with a carbide hopper having an opening provided with an annular valve seat, a carbide feed valve, and a carbide feed valve operating lever, of means connecting the feed valve and the lever comprising a crank member having one portion the axis of which is generally concentric with the center of the valve seat and another portion the axis of which is eccentric with the center of the valve seat. One of such portions is connected to the valve off-center with respect to the latter, and the other portion is connected to the lever so that the valve may be adjusted with respect to the lever into axial alignment with the center of the valve seat. The extent of opening movement of the valve is made adjustable by the provision of a set screw on an arm of the lever which cooperates with the feed lock cam and by the provision of threaded connections between the portions of the crank and the valve and lever, respectively. The crank member preferably consists of an eccentric stud bolt connecting the valve and the lever so that alignment as to height and center lines is afforded by rotating the stud and valve with respect to the lever. Suitable lock nuts and washers are provided for securing the parts in adjusted position.

Referring to the drawing:

Fig. 1 is a fragmentary view, partly in vertical cross-section and partly in side elevation, of a carbide feeding mechanism exemplifying the invention;

Fig. 2 is a top plan view of the carbide feed lever and associated parts;

Fig. 3 is a fragmentary view partly in side elevation and partly in vertical section on line 3—3 of Fig. 1;

Fig. 4 is an enlarged fragmentary view partly in top plan and partly in horizontal section on line 4—4 of Fig. 1;

Fig. 5 is a fragmentary view similar to Fig. 1 of a modification; and

Fig. 6 is a view in end elevation of the modification shown in Fig. 5.

The invention, as illustrated in the drawing, may be embodied in an acetylene generator of the carbide-to-water type described in Patent No. 2,188,278 and which may include a closed casting of symmetrical contour having a water containing and gas generating lower portion and a somewhat similar carbide containing and gas

storage upper portion. A carbide hopper **H** having a downwardly tapering wall or bottom **10** is mounted within the upper portion, the margin of the hopper being rigidly secured to the inner wall of the generator, and the lower end of the hopper being provided with a frusto-conical spout **11** having carbide outlet opening **12** therein. For convenience in attaching adjacent accessories and to facilitate removal of the outlet, the spout **11** is secured to an annular hopper casting or ring **13** by a plurality of bolts **14** and the ring **13** is rigidly secured along a suitable opening in the bottom of the hopper by a frusto-conical flange **15**. The lower portion of the spout **11** is provided with a drip flange **16** which has an internal annular groove **17** adjacent and below the outlet **12**, in which an annular compressible valve seat **18** of soft rubber or the like is removably secured by an annular retainer plate **19** and a spring ring **20**. The opening in the annular valve seat **18** is of substantially the same diameter and substantially in axial alignment with the opening **12** with which it cooperates and forms a part, the flow of carbide from within the hopper **H** through the outlet opening **12** being controlled by a carbide valve **21** that seats on the valve seat **18** and forms a fluid-tight seal through which no water or mixture can enter the hopper to cause generation of gas when the valve is closed.

The carbide valve **21** forms a part of a carbide feed and gas pressure control mechanism **F** which may be detached from the generator as a unit. The control unit **F** is fully described in Patent No. 2,106,972 granted to Maurice P. DeMotte on February 1, 1938 of which Patent No. 2,188,278 is a continuation-in-part. The control unit **F** includes a flexible diaphragm **22** upon which the gas pressure within the generator is balanced by two compression springs **23** and **24** which are compressed within a housing **25** in operative relation with the diaphragm **22** which is operatively connected with the carbide feed valve **21**. The springs **23** and **24** engage a spring pressure plate **26** which engages an inner plate **27**. The diaphragm **22** is clamped between the inner plate **27** and an outer plate **28** by a bolt **29** having a nut **30**, the bolt **29** having a forked end **31** in which is pivotally secured by a pin **32** the inner end of a link **33**. In the outer end of the link **33** is a slot receiving a pin **34** attached to a carbide feed lever **35**. The slot and pin **34** form a lost-motion connection between the diaphragm **32** and the carbide feed lever **35**.

The lever **35** is pivotally mounted on a pin **36** extending across a vertical slot between lugs **37** of a bracket **38** having a flange ring **39**. This flange ring **39** is secured by a plurality of bolts **40** to an outwardly offset flange **41** on the inner end of the housing **25**, the diaphragm **22** being clamped between the ring **39** and the flange **41**.

A spring seat **42** is provided on the carbide feed lever **35** for a compression spring **43** which surrounds the lost-motion connection and extends between the spring seat **42** and the outer plate **28**, urging the pin **34** to the right. Suitable means for holding the carbide feed valve closed when desired, such as when the generator is moved or when it is recharged, is provided which includes a valve closing arm or locking lever **44** integral with the lever **35**, and in operative relation with a feed lock cam **45** having cam surfaces **46**, **47** and **48**, and a lug **49** which forms part of an interlocking means preventing the maximum opening of the valve **21** until a predetermined pressure has been established in the gen-

5 erator. The cam **45** is rigidly mounted on an operating shaft **50**, one end of which is provided with a suitable manually movable member or handle which is located outside of the generator casing, the shaft **50** being mounted in a bearing **51** which is integral with the carbide hopper spout **11**.

10 According to the present invention, an adjustment feature is provided by a slotted screw **52** having a polygonal head **S** mounted on the auxiliary arm **44** of the feed lever **35** for contacting the feed lock cam **45**. The setting of this adjusting screw determines the amount of valve opening obtainable when initially bringing the generator up to operating pressure after the recharging routine (by manually working the external actuating handle of the feed lock cam **45**). The adjustment is secured by means of a cotter pin **53** which passes through the auxiliary arm **44** of the feed lever **35** and a slot **54** in the adjustable screw **52**.

15 According to the present invention, a novel valve stem assembly **55** is mounted in a socket **T** at the free end of the valve lever **35**, which assembly comprises an off-center stud bolt or crank member **56**. The center lines or axes of the threaded end portions **57** and **58** of this stud bolt **56** do not coincide, but are parallel. The spherical segment valve **21** is provided with a socket **V** that is mounted off-center thereof, as shown, and is threaded on the screw **57**, the screw **58** being threaded in the socket **T**. By virtue of employing such component parts, flexibility is afforded in aligning the valve **21** with the annular valve seat **18** in the opening **12** of the carbide hopper **H**. The assembly **55** is likewise adjustable as to height from the free end of the feed lever **35** to the top of the valve **21**. Simplification results thus in the assembly of the generator feed mechanism, since close tolerances are unnecessary to obtain alignment of the valve seat **18** and the regulating spring mechanism prior to installation of the feed lever **35** and the valve **21**.

20 The valve stem assembly **55** includes two lock nuts **59** and **60** on the screws **57** and **58** and two locking washers **61** and **62**. The portions **57** and **58** of the stud bolt **56** are machined with single key ways **63** and **64** extending longitudinally along the threaded part thereof, the washers being provided with inner tabs **65** which project into the key ways of the stud bolt. The washers are thus prevented from rotating with respect to the stud, but are free to move longitudinally thereof. When the desired alignment of the valve **21** with the seat **18** is attained, the lock nuts **59** and **60** are turned tight against the washers **61** and **62** and provide a rigid setting when outer tabs **66** of the washers are bent, as shown, to engage the nuts and the valve and the lever, after all adjustments have been made. It will be obvious that adjustment of the valve **21** as to height and horizontal position is afforded by rotating the stud **56** and valve **21** with respect to the lever **35**. Thus, it is possible to adjust the carbide feed valve **21** accurately with respect to the hopper opening **12** without maintaining close tolerances in the assembly of the feed control unit, generator body, and carbide hopper. The novel assembly **55** provides means for centering the valve as well as for adjusting it upwardly or downwardly, and the lock nuts and washers secure the assembled parts against relative movement after the adjustment.

25 In the preferred form of the invention shown in Figs. 1 through 4, the crank member consists of a stud bolt **56** that is merely bent to provide

the offset screw portions 57 and 58. A modification is shown in Figs. 5 and 6 wherein the means connecting the valve 21 and the valve operating device 35, comprises a crank member 67 having one screw portion 68 the axis of which is generally concentric with the center of the annular valve seat and another screw portion 69 the axis of which is eccentric with the center of the valve seat, the portion 69 being threaded to T, the eccentric socket V of the valve 21 and the portion 68 being threaded to the free end socket T of the device 35, so that the valve 21 may be adjusted with respect to the device 35 into axial alignment with the center of the annular valve seat. Lock nuts 70 and 71 on screw portions 68 and 69 are used to secure the parts in adjusted position, the nuts being physically deformed to prevent any rotation between the parts. The eccentric arrangement of the screws 68 and 69 provides means for aligning the free end of the feed lever, the feed valve, and the valve seat; the eccentric screws also permit adjustment of the height of the feed valve above the lever, as pointed out above in connection with Figs. 1 through 4.

In the position of the feeding mechanism shown in Fig. 1, the cam 45 has been rotated clockwise to bring the cam surface 46 into engagement with the head S of the screw 52 on the arm 44, thereby forcing this arm upwardly and locking the feed valve 21 in closed position. The residual pressure in the generating chamber will cause the diaphragm 22 to remain in a position somewhat to the left of the position it assumed when the valve 21 is open to admit carbide. The springs 23 and 24 will be under compression and the pin 34 will be at or near the right hand end of the slot in the link 33. If the generator remains idle for a considerable period of time, or if the residual gas is drawn off, the drop in gas pressure will permit the springs 23 and 24 to force the diaphragm 22 to the right. The feed lever 35 remains stationary, so the pin 34 will move to the left relative to the slot in the link 33.

If it is desired to resume the feeding of carbide to the generating chamber, the cam 45 is rotated counterclockwise. The initial movement of the cam is limited by engagement of the lug or stop 49 with the head S of nut 52, so that the cam surface 47 is disposed beneath this head S, thereby limiting the opening movement of the valve 21. The small amount of carbide permitted to enter the generating chamber by said initial opening movement of the valve 21 reacts with the wa-

ter therein to generate acetylene gas at a rate just sufficient to cause the pressure to slowly increase. As the pressure rises within the generating chamber, the diaphragm 22 is moved to the left and closes the valve 21. The arm 44 and the head S of screw 52 will then have moved upwardly to their full extent and in this position of the head S the cam 45 may be further rotated in a counter-clockwise direction to move the lock 49 beneath the screw head S and pass the same, bringing the cam surface 48 below the screw head S. When this cam surface 46 is so disposed below the screw head S, the valve 21 may open to its full extent and is then fully under control of the automatic feed control unit.

When it is desired to stop the generation of acetylene gas, the operator will rotate the cam 45 clockwise until the cam surface 46 strikes the screw 52 forcing the arm 44 upwardly and closing the feed valve 21.

While the invention is shown and described as embodied in a carbide-to-water acetylene generator, it is to be understood that it may be embodied in like devices which involve the feeding of other solid materials by gravity, without departing from the invention.

What is claimed is:

1. The combination with an annular valve seat, a valve, and a valve operating device, of means connecting said valve and said device comprising a crank member having one portion the axis of which is generally concentric with the center of said annular valve seat and another portion the axis of which is eccentric with the center of said valve seat, one of said portions being connected to said valve eccentrically thereof and the other portion being connected to said device so that said valve may be adjusted with respect to said device into axial alignment with said annular valve seat.
2. The combination with a valve and an operating device, of a crank member having an end screw threaded to an eccentric socket on said valve and an end screw threaded to a socket on said device.
3. The combination with a valve and an operating device, of a crank member having an end screw threaded to an eccentric socket on said valve and an end screw threaded to a socket on said device, and lock nuts on said screws engaging said valve and device, respectively, for securing the said parts in adjusted position.

RALPH C. PIERSON.
